UNITED STATES PATENT OFFICE.

FRANK E. FARNHAM, OF PROVIDENCE, RHODE ISLAND.

BUTTON.

SPECIFICATION forming part of Letters Patent No. 783,940, dated February 28, 1905.

Application filed October 30, 1903. Serial No. 179,189.

To all whom it may concern:

Be it known that I, FRANK E. FARNHAM, a citizen of the United States, residing at Providence, in the county of Providence and State 5 of Rhode Island, have invented certain new and useful Improvements in Buttons, of which the following is a specification, reference being had therein to the accompanying drawings.

Like letters indicate like parts.

10 Figure 1 is a front elevation of the spring constituting one portion of the post of my improved button. Fig. 2 is a side elevation of the same. Fig. 3 is a side elevation of the rigid plate constituting the other portion of the post of my improved button. Fig. 4 is a front elevation of the same. Fig. 5 is a side elevation of my improved button with the lever-arm thereof shown in its wearing position. Fig. 6 is a side elevation of said button with 15 the lever-arm thereof shown in its entering position. This figure also shows the use of a lining-plate and shoe forming the head of the button. Fig. 7 is a front elevation of the lever-arm mounted in the spring post-section 20 and extending in the plane thereof. Figs. 8, 9, and 10 represent modified forms of the lever-arm. Fig. 11 is a side elevation showing how by a duplication of the lever-arms and spring post-sections my invention forms a 25 cuff-button. In this figure the lever-arms are shown in their wearing position, extending angularly from the post of the button. Fig. 12 is a front elevation of the rigid plate when my invention is embodied in a cuff-button. Fig. 13 is a side elevation of said adaptation 30 of my invention with the lever-arms extending in the entering position.

35 My invention relates to the class of buttons, and more especially to that kind of button in which lever-arms are pivotally mounted on the post of the button and are capable of turning thereon to the extent of ninety degrees.

In the accompanying drawings, in Figs. 1 to 10, inclusive, is shown my invention and parts thereof in that class of buttons known as "pointers" and adapted for use in the neck-band of a shirt to fasten a collar thereon and also to confine a necktie in proper position.

40 A represents a spring-section forming one part of the post of the button. It has a base

with flaring portions a provided with straight bottom edges a' and an intermediate tang or projection a'' . It also has the two square shoulders a^3 at its upper corners, and a curved central extension a^4 , (best seen in Fig. 2,) made 55 with a three-sided seat a^5 , the angular direction of each side of which is illustrated in Fig. 2. Said spring-section A also has a hole a^6 near the base for the passage of a rivet.

B represents a rigid post-section having a 60 base with flaring portion b , provided with straight bottom edges b' and an intermediate tang or projection b'' . It also has the two square shoulders b^3 at its upper corners and a central extension b^4 . The post-section B has 65 a hole b^5 for the reception of a rivet.

C is the lever-arm, transversely slotted near its inner end, as shown at c in Fig. 8, so as to provide an integral cross-bar c' rectangular in cross-section. This lever-arm C may have 70 either of the forms shown in Figs. 7, 8, 9, or 10, and may have slots of different shapes, as there illustrated, to make the same lighter or more ornamental.

The tangs a^2 b^2 are bent in opposite directions, and a button-head or ornamental front may be secured to said bent tangs by soft solder, as illustrated in Fig. 5, or a lining plate or disk D may be used, which is centrally perforated, so that the tangs a^2 b^2 may 80 be inserted through them before bending and afterward may be bent into contact with the under side of said disk or plate D, and thereafter the button-front E may be fastened upon the lining plate or disk D by rolling the edge 85 thereof over it, as seen in Fig. 6.

The parts of my improved button are assembled as follows: The projection a^4 of the spring-post A is inserted through the slot c of the lever-arm C, the cross-bar c' of the latter resting in the seat a^5 of said spring-post A. The two post-sections A and B are placed together in contact, and a rivet F, inserted in the holes a^6 and b^5 , is secured in place and fastens said post-sections together. 95

As best seen in Fig. 5, there is a difference in the length of the post-sections A and B, which is equal to the thickness of the cross-bar c' of the lever-arm C, and, as best seen in Fig. 6, the thickness of the post-section A is 100

the same as that of said cross-bar c' . The consequence is that when the lever-arm C extends at a right angle from the post-sections the outer edge of said cross-bar c' is in line 5 with the outer edge of the shoulders b^3 of the post-section B, as seen in Fig. 5, and when the lever-arm C is extended in the plane of the post-section A the straight edge of the lever-arm c is continuous with and in line with the 10 outer surface of the post-section A, as seen in Fig. 6. In this manner the lever-arm C is prevented from swinging beyond said line.

In Figs. 11, 12, and 13 is shown a construction by which my said invention is adapted to 15 cuff-buttons by duplicating the spring post-sections, as at A', and riveting them respectively on opposite sides of the rigid post-section B'. Two lever-arms C' are mounted by 20 their cross-arms in the seats of the curved ends a^7 of the spring post-sections A'. One of the lever-arms C' may be made longer than the other, if desired, as shown in Fig. 13, to facilitate the entrance of said lever-arms through 25 the button-holes of the cuff and also to enable the wearer to take hold of the lever-arms more easily after they have been inserted through the button-holes for the purpose of turning 30 said lever-arms separately down from the entering position (shown in Fig. 13) to the wearing position. (Shown in Fig. 11.) In making cuff-buttons embodying my said invention the post-section B' preferably has no tang, and the ornamental button head or front is secured in position by means of the bent tangs a^8 .

35 The rigid post-section B (or B') serves not only as a firm support to which the spring post-sections may be riveted, but is useful as providing a wearing-plate against which the square end of the cross-bar c' of the lever- 40 arms C may bear and is especially important as constituting a locking-surface to receive the contact and pressure of the cross-bar c' of the lever-arm C by the spring action of the curved end a^4 of the spring post-section A.

Thus each lever-arm C' has an absolutely independent action without any interference or contact with the other of the lever-arms C'. 45

I claim as a novel and useful invention and desire to secure by Letters Patent—

1. In a button, the combination of a rigid 50 post-section having opposite plane parallel surfaces, a spring post-section riveted near one end to the rigid post-section and formed with a three-sided seat at its opposite end, and a lever-arm having a slot to receive the last-named end of the spring post-section and provided with a cross-bar which is rectangular in cross-section, three sides of which are in contact and engageable with the three sides respectively of said seat in the spring post-section and a fourth side of which is in contact and engageable with the inner plane surface of said rigid post-section, substantially as described. 55

2. In a button, the combination of a spring 60 post-section A, having the two shoulders a^3 and the intermediate curved projection a^4 which is provided with a seat a^5 , the rigid post-section B having the shoulders b^3 and the intermediate straight projection b^4 , said projections a^4 and b^4 being flush with each other at the ends thereof but said shoulders a^3 being distant from the shoulders b^3 to an extent approximately equal to the thickness of the post-section A, the rivet F fastening said post-sections A and B together near the opposite ends thereof, and a lever-arm C having a slot c through which the projection a^4 of the post-section A extends and also having a cross-bar c' rectangular in cross-section and mounted 70 between the post-sections A, B, in the seat a^5 , substantially as described. 75

In testimony whereof I affix my signature in presence of two witnesses.

FRANK E. FARNHAM.
